222,382

SEWER CLEANER HOUSING

Charles E. Freese, Erie, Pa., assignor to Emerson
Electric Co., St. Louis, Mo.

Filed Apr. 22, 1970, Ser. No. 22,573

Term of patent 14 years

Int. Cl. D15—05

U.S. Cl. D49—10

FIG. 1 is a side elevational view;
FIG. 2 is a rear elevational view;
FIG. 3 is a front elevational view; and
FIG. 4 is a top plan view.

The side of the sewer cleaner housing opposite FIG. 1 is of the same general appearance as the side shown except for the omission of the handle and cleats.

I claim:

The ornamental design for a sewer cleaner housing, as shown and described.
